US00D540566S

(12) **United States Design Patent** (10) **Patent No.:** **US D540,566 S**
(45) **Date of Patent:** **** Apr. 17, 2007**

(54) **PRODUCT DISPLAY**

(75) Inventors: **Jonah M. Scholen**, Minneapolis, MN (US); **Blake Nielsen**, Schaumburg, IL (US); **Raul S. Romero**, Ajax (CA); **Aaron Guiden**, Fraserville (CA)

(73) Assignee: **Target Brands, Inc.**, Minneapolis, MN (US)

(**) Term: **14 Years**

(21) Appl. No.: **29/201,783**

(22) Filed: **Mar. 19, 2004**

(51) **LOC (8) Cl.** **06-04**

(52) **U.S. Cl.** **D6/449; D6/448**

(58) **Field of Classification Search** D6/449, D6/451, 455, 457, 466, 468, 471, 474; 211/4, 211/13.1, 49.1, 85.2, 134; 108/159; D7/509; D14/299; D28/38; D16/245; 206/6.1; 304/568.2
See application file for complete search history.

(57) **CLAIM**

The ornamental design for a product display, as shown and described.

DESCRIPTION

FIG. 1 is an isometric view of a product display according to the invention.

FIG. 2 is a front view of a product display, according to the invention.

FIG. 3 is a rear view of a product display, according to the invention.

FIG. 4 is a top view of a product display, according to the invention.

FIG. 5 is a bottom view of a product display, according to the invention; and,

FIG. 6 is a right side view of a product display, according to the invention. The left side view is a mirror image of the right side view and is omitted.

In the drawings, the broken lines represent environmental structure forming no part of the claim.

1 Claim, 6 Drawing Sheets
